UNITED STATES PATENT OFFICE

171,919

COMBINED TELEVISION CABINET AND PLANTER

Mike Zedick, Akron, Ohio

Application July 8, 1953, Serial No. 25,850

Term of patent 7 years

(Cl. D56—4)

To all whom it may concern:

Be it known that I, Mike Zedick, a citizen of the United States, residing at 1616 Simcoe Avenue, Akron, State of Ohio, have invented a new, original, and ornamental Design for a Combined Television Cabinet and Planter, of which the following is a specification, reference being had to the accompanying drawing, forming a part hereof.

Fig. 1 is a front elevational view of a combined television cabinet and planter, showing my new design.

Fig. 2 is a top plan view thereof.

Fig. 3 is a side elevational view thereof.

I claim:

The ornamental design for a combined television cabinet and planter, as shown.
